COIN GAUGE

Charles F. Barothy, Hinsdale, Ill., assignor to
 Western Electric Company, Incorporated, New
 York, N. Y., a corporation of New York

Application December 11, 1935, Serial No. 53,947

5 Claims. (Cl. 194—102)

This invention relates to coin gauges and more particularly to coin gauges for coin collectors such as those employed at telephone pay stations.

One type of telephone pay station coin collector, for example, such as that disclosed in the U. S. patent to O. F. Forsberg 1,043,219, issued November 5, 1915, comprises a housing upon which is mounted what is commonly called a coin gauge comprising a metallic structure with a plurality of openings for receiving coins of different denominations. Associated with each of these openings is a slot for guiding the deposited coin into the housing for subsequent collection or refund, depending upon whether the desired services are secured. A coin gauge of this type has heretofore been cast of a relatively soft metal and plated with a harder metal. It has been a relatively expensive article to produce, requiring many and widely different operations in its production. The size of each opening into which the coins are placed must be held to close limits in order to gauge properly each coin for maximum diameter, and when the gauge is electroplated with a metal such as chromium, very careful control of the plating process is required to insure that the thickness of the plating is such as to meet manufacturing limits upon the size of the finished opening and provide the necessary protection against wear.

An object of this invention is the provision of an improved multi-part coin gauge having a construction permitting accurate forming and assembly of the parts with a required structural strength and which is economical to manufacture and durable in service.

In accordance with the above object, the invention contemplates, in one embodiment thereof, as applied to a telephone pay station coin collector a coin gauge comprising front, rear and center integral sections punched and formed from stainless steel and secured together by welding. The front or housing section alone serves to gauge the diameter of the coins and the center and rear sections which are assembled as a unit before their assembly with the front section serve to gauge the thickness of the coins independently of the front section. In an alternative construction the center section comprises two punched and formed parts instead of one.

The invention will be better understood by reference to the following detailed description taken in connection with the accompanying drawing, in which

Fig. 1 is a side view of a telephone pay station coin collector of a type capable of employing an improved coin gauge of this invention;

Fig. 2 is a front view on an enlarged scale of the coin gauge illustrated in Fig. 1;

Fig. 3 is a horizontal sectional view taken along the line 3—3 of Fig. 2;

Fig. 4 is a perspective view of the assembled center and rear sections before the front or housing section is assembled therewith;

Figs. 5 and 6 are vertical sectional views taken along the lines 5—5 and 6—6 of Fig. 2, and

Fig. 7 is a vertical sectional view similar to the section 5—5 of Fig. 2 of an alternative construction employing a two-part center section.

Referring now to the drawing and particularly to Fig. 1 wherein there is shown a telephone pay station coin collector of the general type disclosed in the herein mentioned Forsberg patent, the numeral 10 indicates an upper housing for the coin collector having on its upper wall 11 a coin gauge 12 embodying the features of this invention. One embodiment of the coin gauge 12 as shown in Figs. 2 to 6, inclusive, has a plurality of openings in its front wall through which coins of different denominations, such as five, ten and twenty-five cent pieces may be deposited for passage through channels, one corresponding to each of the openings provided in a laterally inclined coin chute 13 (Fig. 30). The coin chute channels guide the coins deposited into the openings in the coin gauge 12 to mechanism (not shown), which eventually discharges the coins either into a cash compartment or a refund tray, depending upon whether the desired services are secured or not.

The coin gauge 12 (Figs. 2 to 6, inclusive) comprises cooperating front, rear and center sections 16, 17 and 18, respectively. Each of the sections comprising one integral piece of metal, 40 preferably stainless sheet steel, produced by suitable blanking, perforating and forming operations in accordance with known practices in the art of metal working. The front section 16 includes front, top and end walls 19, 20 and 21, 45 respectively, and a foot 24 extending forwardly from the front wall, the end walls 21 being inclined outwardly at similar angles from the top wall 20 to the plane of the lower surface of the foot 24. Formed in the front wall 16 are three 50 coin receiving and diameter gauging apertures 25, 26 and 27 for five, ten and twenty-five cent pieces, respectively. Each of the apertures 25, 26 and 27 is surrounded by an annular flange 30, 31 and 32, respectively, the inner peripheral 55

faces of the flanges being flush with the inner faces of the apertures, and each flange extends rearwardly from the inner face of the front wall 16 for a predetermined different distance, the 5 reason for which will be described hereinafter. Each aperture 25, 26 and 27 has a diameter just slightly greater than the diameter of the coin which each opening is designed to receive, thus serving to gauge the diameter of the coins inserted therein.

The center section 18 comprises a plate-like member 33 having three forwardly extending embossments 36, 37 and 38 formed thereon, which are open at their lower ends, the embossments being provided at their upper ends with apertures 39, 40 and 41, respectively, substantially concentric with the apertures 25, 26 and 27, respectively, in the front section 16. Each of the embossments 36, 37 and 38 extends downwardly at a slight angle from the vertical, each angle differing from the angle of the others and at their lower ends the embossments as well as the portions of the plate 33 therebetween extend for a slight distance below the plane of the 25 lower face of the foot 24 of the front section 16, as indicated at 42 (Figs. 2 and 5). The lower ends of the embossments and the portions of the plate 33 therebetween extend into an opening or slot 43, indicated in dotted lines (Fig. 30 5), formed in the upper wall 11 of the coin collector housing 10, when the assembled coin gauge is secured in position thereon and serve to prevent strips of paper or other material from being inserted under the coin gauge to block the 35 passage of the coins into channels provided in the coin chute 13, which channels communicate with the lower open ends of the angular disposed embossments.

The rear section 17 comprises a plate-like member 45 having end flanges 46, inclined similar to the end walls 21 of the front section 16 and fitting therewithin and a rearwardly extending foot 47 disposed in the plane of the foot 24 of the front section. Formed in the member 45 is a single embossment 48 having a size and configuration which permits it to fit snugly within the embossment 38 formed in the center section 18 (Figs. 3 and 5). The rear and center sections 17 and 18, respectively, have a substantially identical configuration along their top and ends, as viewed in front elevation, the center section 18 being slightly smaller than the rear section, as indicated at 49 (Figs. 2, 3, 5 and 6) and, as described hereinbefore, the lower end of 55 the center section extends below the front and rear sections along its bottom. The peripheral edge face of the rear section 17 along its top and ends fits snugly against the inner continuous face of the top 20 and end walls 21 of the 60 front section 16.

It will be observed, referring particularly to Figs. 2 to 6, inclusive, that the height or distance that each of the embossments 36, 37 and 38 is raised or extended from the front face of the plate 33 differs in the case of each embossment and in assembled relation the rear face of the plate 33 comprising the center section 18 abuts the front face of the plate 45 comprising the rear section 17. Thus the cooperating spaced rear 65 faces of the embossments 36 and 37 and the front face of the plate 45 provide channels 52 and 53 for the passage of five and ten cent pieces inserted into the coin gauge through the apertures 25 and 26, respectively. Likewise the 70 spaced rear face of the embossment 38 and the 75

front face of the embossment 48 on the rear section 17 provide a channel 54 for the passage of twenty-five cent pieces inserted into the coin gauge through the aperture 27. The spacing between the opposed faces forming each of the 5 channels 52, 53 and 54 are slightly greater than the thickness of the coin which each channel is designed to receive, the channels thus serving to gauge the thickness of coins passing thereto. It will also be observed that the twenty-five cent channel 54 is arranged forwardly of the five and ten cent channels 52 and 53, respectively, which are in substantial alinement. This is so in order that the completed coin gauge 12 may be employed in conjunction with the 15 particular coin chute 13 used in the coin collector of the general type disclosed in the hereinbefore mentioned Forsberg patent.

The annular flanges 30, 31 and 32 surrounding the apertures 25, 26 and 27, respectively, of the 20 front section 16 and which extend rearwardly from the inner face thereof, abut at their annular edges, in the case of the flanges 30 and 31, the outer faces of the embossments 36 and 37 surrounding the apertures 39 and 40, respectively, and in the case of the flange 32 the end thereof is entered in the aperture 41 of the embossment 38, when the front section is assembled with the center and rear sections. The 25 different lengths, hereinbefore described, of the flanges 30, 31 and 32 it will be apparent are necessary due to the different distances the outer faces of the embossments 36, 37 and 38 are from the outer face of the center plate 33. The flanges 30, 31 and 32 serve as means for 30 guiding the coins inserted through the apertures 25, 26 and 27 into the downwardly extending channels 52, 53 and 54 communicating therewith, respectively. At the lower open ends of the embossments 36, 37 and 38 the front walls 40 thereof are slightly flared (Figs. 5 and 6) to provide greater clearance at these points to insure the passage of the coins from the channels 52, 53 and 54 into the coin chute channels arranged therebelow.

To insure that the coins inserted in the apertures 25 and 26 and guided into the downwardly extending channels 52 and 53 by the flanges 30 and 31, respectively, will freely pass into the channels without meeting obstruction from the 50 annular edge faces of the apertures 39 and 40 of the embossments 36 and 37, respectively, the latter apertures are made slightly greater in diameter than the apertures 25 and 26, as clearly shown in Figs. 2, 5 and 6. In assembling 55 the front section 16 with the center and rear sections 18 and 17, respectively, the inner peripheral edge faces of the flanges 30 and 31 are arranged flush with the similar faces of the apertures 39 and 40, respectively, at their lower-60 most points. This arrangement provides a continuous flush surface for the five and ten cent coins to slide upon from their entrance into the apertures 25 and 26 until they drop into the channels 52 and 53, respectively. Since the 65 flange 32 for guiding the twenty-five cent coins is entered in the aperture 41 of the embossment 38 the above described provision for insuring the free passage of the five and ten cent coins is not necessary. Struckout from the front wall 70 of the embossment 38 at the left side of the center section is a small embossment 55 serving as a stop member which in assembling the front section with the center and rear sections abuts the inner face of the front section and is effec-75

tive to position them in parallel alignment during assembly. The abutting annular edges of the flanges 30 and 31 of the front section and the outer faces of the embossments 36 and 37, respectively, on the center section it will be apparent serve the same purpose at the right side of these sections as the stop member 55 at the left side thereof.

In order to facilitate attaching the coin gauge 12 to the top wall 11 of the upper housing 10 and over the slot 44 the feet 24 and 47 of the front and rear sections 16 and 17, respectively, are provided with apertures 56 (Fig. 3) which register with apertures formed in the housing wall through which apertures, screws, bolts or rivets are extended to secure the coin gauge in position. The apertures 56 in the rear section are elongated to take care of slight variations in the distance between these apertures and the apertures in the front section after the coin gauge has been assembled, which might vary from the spacing between the corresponding apertures in the housing wall 11.

Small perforations 57 are provided in the rear plate 45 opposite the coin receiving apertures 25, 26 and 27 of the front section 16 in order to facilitate the removal of any slug or coin which has become wedged in the gauge.

The front face of the rear plate 45 has depressed therein characters 62, such as numerals "5", "10" and "25", which are visible through the coin receiving openings 25, 26 and 27, respectively, to indicate the five, ten and twenty-five cent openings in the gauge, the depressed surfaces of the characters being filled in or colored, for instance, with a black enamel, or other finish, to set the characters out against the surrounding stainless steel surface of the plate 45.

In assembling the front, rear and center sections 16, 17 and 18, respectively, to complete the coin gauge 12 the rear and center sections are first brought into abutting relation, as shown in Figs. 3 and 4, in which position the embossment 48 of the rear section is entered in the embossment 38 of the center section and the peripheral edge face of the center section will be positioned slightly inside the similar face of the rear section, as indicated at 49 (Fig. 2). The center and rear sections while thus related and held by suitable clamping means are then permanently attached or united at a plurality of points by spot welding, as indicated at 60 (Fig. 4). Thereafter the front section 16 is clamped in a suitable manner with the required pressure against the assembled center and rear sections with the coin guiding flanges 30, 31 and 32 thereof abutting or aligned, as hereinbefore described, with the apertures 39, 40 and 41, respectively, of the center section, the peripheral edge face of the rear section along its top and ends fitting snugly against the inner continuous face of the top 20 and end walls 21 of the front section. While so related the end flanges 46 of the rear section 17 are permanently attached or united to the end walls 21 of the front section 16 at both ends of the assembly at a plurality of points by spot welding, as indicated at 61 (Fig. 6). This completes the assembly of the coin gauge and thereafter it is polished and buffed on the top, sides, front and top of front foot and the back surface of the rear section may be given a coat of black enamel.

In Fig. 7 another embodiment of the invention is illustrated, wherein center and rear sections 63 and 64 of the coin gauge at the twenty-five

cent coin portion thereof are constructed differently than these portions in the structure shown in Figs. 2 to 6, inclusive. The rear section 64 in Fig. 7 is not embossed as in the previously described coin gauge structure to form the rear wall of a downwardly extending coin thickness gauging channel 65. Instead the center section 63 is embossed, as indicated at 66, to a plane identical to that of the embossment 48 on the rear section of the first embodiment. To provide the front wall of the channel 65 a short plate 67 extending across the twenty-five cent portion and to the adjacent end of the gauge is welded to the center section 63, the plate 67 being embossed, as indicated at 68, to a plane identical to that of the embossment 38 on the center section of the first embodiment. A perforation 69 is formed in the wall of the embossment 68 in line with the perforation 57 provided in the rear section hereinbefore described and for a similar purpose. Other than the noted differences in construction the two described coin gauges and the method of producing them are identical.

It is evident that coin gauges constructed, as above described, from a plurality of sections formed from stainless sheet steel molecularly united into an integral structure will have a required strength, the struck out embossments on the center and rear sections serving in addition to their described functions for adding rigidity to the assembly. Also the sections may be inexpensively formed by simple punch press operations and readily assembled and welded together. In addition by fabricating them from stainless sheet steel great wearing quality will result. Furthermore, due to the fact that the front section alone gauges the diameter of the coins while the center and rear sections, which are assembled as a unit before their assembly with the front section, gauges the thickness of the coins independently of the front section, an accurate construction and assembly of the parts is facilitated.

Although the embodiments of this invention as herein illustrated and described are particularly well adapted for use in connection with telephone pay station coin collectors, it should be understood that the invention is capable of other applications and should be limited only by the scope of the appended claims.

What is claimed is:

1. A coin gauge comprising united front, rear and center sections punched and formed from sheet metal, said front section having a coin receiving and diameter gauging aperture, said center section abutting said rear section and having an embossment formed thereon provided with an aperture substantially concentric with the aperture in said front section, the opposed spaced faces of the rear section and that of the embossment on said center section forming a channel of predetermined depth communicating by means of the aperture in the embossment with the coin diameter gauging aperture for gauging the thickness of coins passing thereto.

2. A coin gauge comprising united front, rear and center sections punched and formed from sheet metal, said front section including front, top and end walls, the front wall thereof having a coin receiving and diameter gauging aperture therein, said rear and center sections being an assembled unit before the front section is united thereto, comprising a rear plate having end

flanges fitting within and united to the end walls of the front section, and a center plate abutting the rear plate and having a vertically extending embossment thereon provided with an aperture 5 at its upper end substantially concentric with the aperture in said front section, the opposed faces of the rear plate and the embossment on said center plate forming a channel of predetermined depth communicating by means of the aperture in 10 the embossment with the coin diameter gauging aperture for gauging the thickness of coins passing thereinto.

3. A coin gauge comprising united front, rear and center sections punched and formed from 15 sheet metal, said front section having a plurality of spaced coin receiving and diameter gauging apertures and a coin guiding flange surrounding each of the apertures, said rear and center sections being united in abutting relation and 20 having forwardly extending embossments of predetermined different depths formed thereon, each of the embossments on the center section being provided with an aperture substantially 25 concentric with one of the apertures and its surrounding flange in said front section, the opposed spaced faces of the rear section and those of the embossments on said center section forming channels communicating by means of the apertures in the embossments with the coin diameter gauging apertures for gauging the thickness of coins passing 30 thereinto.

4. A coin gauge comprising united front, rear and center sections punched and formed from sheet metal, said front section having a plurality 35 of spaced coin receiving and diameter gauging apertures and a coin guiding flange flush with the inner surface of each of the apertures, said rear and center sections being united in abutting relation, the center section having forwardly

extending embossments of predetermined different depths formed thereon, each provided with an aperture substantially concentric with the apertures in said front section, the rear edge faces of two of said flanges abutting forward 5 faces of the corresponding embossments on said center section, the third flange on said front section being entered in the aperture of its corresponding embossment, a forwardly extending embossment formed on the latter embossment 10 abutting the rear face of said front section, the abutting faces of the embossments, edge faces of said flanges and the rear face of said front section cooperating as stop surfaces in assembling and uniting the sections, the opposed faces 15 of the rear section and those of the embossments on said center section forming channels communicating by means of the apertures in the embossments with the coin diameter gauging apertures for gauging the thickness of coins passing 20 thereinto.

5. A coin gauge comprising united front, rear and center sections, said front section having a coin receiving and diameter gauging aperture and a coin guiding flange flush with the inner 25 surface of the aperture and abutting the forward face of said center section, said center section abutting said rear section and having an embossment formed thereon provided with an aperture designed and arranged for receiving a 30 coin passing thereinto from the aperture and flange of said front section, the opposed spaced faces of the rear section and that of the embossment on said center section forming a channel of predetermined depth for gauging the 35 thickness of coins passing thereinto from the aperture in the embossment.

CHARLES F. BAROTHY.
